UNITED STATES PATENT OFFICE.

WILLIAM H. JAXHEIMER, OF PHILADELPHIA, PENNSYLVANIA, ASSIGNEE TO SMITH DRUM & COMPANY, OF PHILADELPHIA, PENNSYLVANIA, A CORPORATION OF PENNSYLVANIA.

LOCKING DEVICE FOR WASHING-MACHINE CYLINDERS.

Application filed July 30, 1927. Serial No. 209,618.

My invention relates to washing machines and has for its object to provide a locking device for the sliding door of the cylinder of the machine of such construction that it can be easily operated and which preferably includes a pivoted finger which is operated in synchronism with the locking bolt so as to be retracted when the cylinder is closed and locked and to project outward into the 10 door opening of the cylinder casing when the cylinder door is open.

The nature of my improvements will be best understood as described in connection with the drawings which illustrate portions 15 of a washing machine casing and cylinder provided with the usual door closed openings and equipped with my improved locking device.

Figure 1 is a front view of the cylinder 20 and its door, the door being in closed position and provided with my improved locking device.

Figure 2 is a cross sectional view of the parts shown in Fig. 1, taken on the line 25 1-1 of Fig. 1.

Figure 3 is a similar sectional view showing the door of the cylinder in open position and the finger of the locking device projecting into the door opening of the 30 casing.

Figure 4 is a plan view of my improved locking device.

Figure 5 is a cross sectional view on the line 5-5 of Fig. 4, and

Figure 6 a cross sectional view on the line 6-6 of Fig. 4.

A indicates the cylinder casing having a door opening A¹, having a door J indicated as in open position, the edge of which is indicated in the drawing. B is the cylinder of the machine having a door opening B¹ and provided with guides indicated at B³ beneath which lie the lateral edges of the door C, which is a sliding door having a hook C¹ at its rear edge which engages a similar hook B² of the cylinder when the door is closed, as shown in Fig. 2. This sliding door has a depressed pocket C² formed at its front edge in which is located and secured the depressed locking bolt housings DD. These bolt housings are formed with open faced chambers D¹ near one lateral side of which extends upwardly a rib d² providing the chamber all so located as to provide

an open space D² in which the fingers of the operator can be located while his thumb extends into the chambers D¹. D³ and D⁴ are aligned openings in the walls of the housing in which is located the bolt. The opening D⁴ is as shown closed by a screw cap E between which and the end of the bolt F is located a spring E¹. F¹ is the locking end of the bolt. F² a transverse slot formed in the under side of the bolt and F³ a pin projecting from one side of the bolt. G is a pivot pin located in the chamber D¹ and on which is pivoted the bolt actuating lever G¹ having as shown an upwardly extending grip G² at its free end and an upwardly extending pin G³ which lies in the slot F² of the bolt. H is a pivot pin secured in the side of the chamber D¹ and on which is pivoted a finger H¹ which in retracted position lies in the chamber D¹ as shown in full lines in Figs. 4, 5 and 6 but which can be turned up to the position shown in dotted lines in Fig. 5. This finger is interconnected with the bolt by means of a forked end H² which extends over the pin F³ projecting from the side of the bolt.

I, best shown in Figs. 2 and 3, indicates a strip secured to the wall of the cylinder and having at its ends bolt holes, one indicated at I¹ to receive the bolt when the door is closed and one indicated at I² to receive the bolt when the door is fully open. The detent hole I² is shallow so that while it serves to lock the door in open position it does not permit the bolt to move out to its full throw.

In operation, when the door is closed, as indicated in Figs. 1 and 2, the end F¹ of the bolt is engaged in the bolt hole I¹ and the position of the parts is such that the finger H¹ is fully retracted within the chamber D¹. When it is desired to open the door the operator inserts his fingers in the chamber D² and against the rib d² while his thumb extending into the chamber D¹ engages the grip G² of the lever G¹, enabling the operator to shift the lever from the position shown in full lines to that shown in dotted lines in Fig. 4, with little effort and much power. This motion of the lever draws back the bolt, which in moving back through the described mechanism throws the finger H¹ into upright position. The door is then slid to open position and a rib I³ is provided on

the strip I to contact with the end of the bolt and keep it in retracted position. When the door is fully opened the bolt is engaged with the shallow bolt I² locking the door in open position but still keeping the finger H¹ in outwardly extending position so that it is only when the door is closed and bolted that the door of the casing can be closed.

Having now described my invention, what I claim as new and desire to secure by Letters Patent is:

1. In combination with a washing machine cylinder having a sliding door and a bolt hole formed to register with a locking bolt when the door is closed, a depressed open faced bolt housing secured to the door formed with an upwardly extending rib dividing the housing into two compartments of unequal size and adapted to serve as a finger grip for an operator in actuating the bolt lever, a vertical pivot pin located in the larger compartment of the housing, a bolt passing through the housing and a bolt actuating lever pivoted on the vertical pivot and

movable horizontally in the larger housing compartment.

2. In combination with a washing machine cylinder having a sliding door and a bolt hole formed to register with a locking bolt when the door is closed, a depressed open faced bolt housing secured to the door formed with an upwardly extending rib forming a finger rest for the hand of an operator, a spring actuated bolt extending through the depression in the housing, a bolt actuating lever pivoted in the depression having its free end disposed in the housing opposite to the rib in position to be engaged by the thumb of the operator, a finger pivoted in the depression in the housing and movable between positions in which it lies entirely within said depression and extends upward therefrom and means actuated by the movements of the bolt whereby said finger is retracted within the depression when the bolt is in locking position and turned outward when the bolt is retracted.

WILLIAM H. JAXHEIMER.
